DESIGN FOR A BROOCH OR SIMILAR ARTICLE

Lester Gaba, New York, N. Y., assignor to Albert Weiner, Providence, R. I., doing business as Albert Manufacturing Company

Application February 15, 1938, Serial No. 75,137

Term of patent 3½ years

To all whom it may concern:

Be it known that I, Lester Gaba, a citizen of the United States and a resident of New York, in the county of New York and State of New York, have invented a new, original, and ornamental Design for a Brooch or Similar Article, of which the following is a specification, reference being had to the accompanying drawing, forming part thereof, and in which

Fig. 1 is a front view of a brooch or similar article showing my new design; and

Fig. 2 is an edge view thereof.

The distinctive feature of the present design resides in the positioning of elongated, beveled stones along the edge of the wing and at the base of the tail of an eagle outline, the eagle outline itself being formed by a plurality of round stones closely packed together.

I claim:

The ornamental design for a brooch or similar article substantially as shown and described.

LESTER GABA.
